LIQUID FUEL BURNING APPARATUS

Milton A. Powers, Detroit, Mich., assignor, by
mesne assignments, to The Timken-Detroit
Axle Company, a corporation of Ohio

Application August 20, 1934. Serial No. 740,698

3 Claims. (Cl. 158—77)

This invention relates to a novel apparatus for burning liquid fuel in accordance with what has come to be known recently as the "wall flame principle". More specifically, the invention 5 relates to rotary power burners for use in small installations, such as hot water heaters.

In most cases in the prior art the rotating parts of rotary oil burners are separately assembled and are of considerable size and weight. 10 This necessitates considerable power for their operation, and it is evident that high stresses are inherent due to the centrifugal forces set up as a result of which the parts must be made extremely rigid. Perhaps for this reason, in many 15 prior devices fuel oil is supplied at approximately the level at which it is to be discharged so that additional work will not be required of the operating motor. However, in order to supply the fuel oil at this point, it is necessary in many 20 installations to have a special device to perform this one function. It is highly desirable to use a single motor to perform all the work.

The rotating parts of my device are assembled as a unit and are of relatively small diameter so that the centrifugal force developed thereby is negligible, which permits the use of very light parts. Consequently, the power required to rotate such parts is exceedingly small, and I am able to use a relatively small operating motor 30 both for this purpose and to raise the fuel oil to the level at which it is to be discharged. Therefore, one of the principal objects of this invention is to provide a rotary oil burner having small parts of light weight and operated with a minimum of friction by a relatively small motor.

Conventional oil burning systems ordinarily have two types of control sets. One set may be termed temperature controls, and the other, safety controls. The former govern the normal 40 operation of the system and depend for their operation on the temperatures of the water, air, or whatever is heated by the flame. The latter govern the safe operation of the system, and operate only when there is a failure of some part 45 of the system to operate normally. Prior rotary power burners have embodied a multiplicity of such controls in order to insure safe and positive operation, such as complicated magnetic oil valves, stack temperature-operated electric shut-off switches and myriads of other electrical devices. In other words, complicated systems have been set up to insure safe operation. In my invention I have discarded such complicated systems. I have made the fuel the safety control 50 of the system and have simplified it to the ex-

tent where it acts of itself. I employ only one temperature control. This is connected into the electric circuit between the power source and the motor so that when it is open the motor will stop, no fuel oil will be raised to the discharge 5 level and no combustion will take place.

Therefore, another of the principal objects of this invention is to provide a rotary power burner with a simple, positive safety control system. More specifically, it is an object to devise a novel 10 means whereby the flow of fuel in and of itself operates to stop operation of the burner.

A further object is to provide a doubly-safe control system whereby the flow of fuel may be stopped by devices in the fuel circuit in either 15 or both sides of the burner fuel inlet and/or outlet. More specifically in this connection it is an object to provide an oil shut-off device which connects with the oil feed line and also with the combustion chamber.

A further object is to provide a rotary fuel burning system which will operate safely with only one thermostatically-controlled electric switch.

A further object of this invention is to provide a liquid fuel burner in which the flow of fuel from the source of supply is automatically cut off upon failure of the liquid level valve to function or upon failure of the burner to ignite.

Another object of the present invention is to provide a control system for a liquid fuel burner in which the operation of the motor is controlled by the temperature of the heat absorbing medium.

Therefore, it will be seen that the primary or general object of the present invention is to provide a rotary liquid fuel burner, which is extremely simple to manufacture—and hence, inexpensive—easy to install and economical and safe to operate.

The foregoing and further objects of the invention will fully appear from a study of the following details and description when taken in conjunction with the accompanying drawings.

Referring now to the drawings wherein like numerals are employed to designate like parts wherever they occur,

Figure 1 is a vertical sectional view of a preferred embodiment of my invention taken on 50 the line 1—1 of Figure 2. It shows the oil metering and level valve out of position for the sake of clarity.

Figure 2 is a horizontal sectional view taken on the line 2—2 of Figure 1, and

Figure 3 is an enlarged sectional view showing the oil drain outlet at the hearth, as seen on the line 3—3 in Figure 2.

The complete burner A is mounted centrally in a combustion chamber C with its oil delivery level approximately on a level with the lower portion of the water legs of water heater D, which is supported on a base B. Oil is supplied to the burner from a conventional storage tank to an oil metering and constant level valve F, and thence to the burner A.

Referring particularly to Figure 1, the oil and air supply mechanism proper consists essentially of a stationary portion 1 and a rotating portion 2. Said stationary portion consists of an outer casing 4 of cuplike section having an upstanding central boss 6 therein. Approximately midway down the inner surface of said casing 4 is placed the stator portion 8 of the propelling electric motor. Said stator portion 8 is suitably positioned and retained in casing 4 by being press-fitted into a cylindrical surface and against a shoulder provided therefor in said casing. The stator embodies coils 9 which are so disposed as not to interfere with the type of air circulation hereinafter described.

The upper portion of said casing has a series of apertures 10, extending intermittently around the outer periphery for the purpose of admitting air. Placed around said apertures 10 and located in a groove 15 provided therefor in casing 4 is an air shutter 11 for the purpose of controlling the air supply. The air, that is thus supplied for combustion, serves during its passage to cool the motor, particularly the windings 9 thereof. Said shutter is provided with ears 12 at its ends, which may be clamped together by means of screw 14, in order to lock said shutter in place. A series of lugs 17 are provided on the outer periphery of casing 4 approximately midway its height, said lugs being apertured to receive bolts for bolting said burner in position.

The central upstanding boss 6 has a tapered aperture extending through the bottom of casing 4 for the purpose of press-fitted receiving a bronze sleeve 22. Said sleeve has an aperture running therethrough, the upper portion 24 of which is of a lesser diameter than the lower portion 25. The lower extremity of portion 25 is suitably threaded to receive a special screw 26 which seals said extremity by means of clamping packing 28 between the screw head and the lower end of said sleeve. Mounted on top of screw 26 and within portion 25 is a hardened plug 30 which is substantially cylindrical in shape and for a purpose to be described later.

A chamber sealed at its lower portion thus is formed on the inside of sleeve 22. This chamber is utilized as a lubricant reservoir to insure lubrication of a rotating shaft to be described later.

The outside diameter of sleeve 22 above the tapered portion is of uniform size and of a smooth surface. Surrounding said last-mentioned portion is a space 37 formed by an upstanding cylindrical extension of upstanding boss 6 which likewise has smooth inner and outer diameters of uniform size. Fuel oil is admitted to said space 37 by means of aperture 40 which connects with the outer periphery of casing 4 and passage 42. Fuel oil is supplied to aperture 40 from valve F.

The rotating portion 2 of the distributing head includes an armature or rotor 46 which is attached as a unit on a casting 50. Casting 50 has a lower cylindrical portion which is in-

teriorly threaded as shown, the lower portion of the threads dipping into the fuel oil contained in space 37. When said threaded portion is rotated a pumping or lifting action is initiated and the fuel oil is carried upwardly.

The detailed motor and pump assembly are claimed in the pending divisional application Serial No. 95,413, and accordingly will not be further described herein.

Connecting with the upper portion of thread 52 and disposed at an angle therewith are two diametrically opposite apertures and have press-fitted therein the lower ends of several oil flinger tubes 58. Said flinger tubes are bent at the upper extremities to form nozzles 60. The upper portion of sleeve 22 has a reduced diameter to afford more space to accumulate fuel oil which has previously been raised by means of threads 52.

Extending centrally through an aperture provided therefor in casting 50 and in press-fitted engagement therewith is shaft 62 having its lower portion hardened and ground. Said shaft has in its lower portion a shallow hole which is so sized as to rotatably receive a hardened ball 66. Shaft 62 is so positioned with respect to casting 50 that when the rotating portion 2 is lowered so that ball 66 rests on hardened block 30, armature 46 will be in register with stator 8, the upper surface of cylindrical portion 38 will clear the registering portion of casting 50 and the lower surface of cylindrical portion 51 will not abut the lower surface forming space 37. The shaft 62 and casting 50 of course rotate in unison. In this manner, the rotating portion 2 is supported solely upon hardened block 30 so that the only friction resisting turning of said rotating portion results from the contact of ball 66 with hardened block 30 and the friction of shaft 62 within aperture 24 of sleeve 22.

A fan 70 is provided on the upper portion of shaft 62 and consists essentially of a disk 72 of sheet metal having at its central portion a plug 74 shear-riveted in place as at 76. Said plug 74 is centrally apertured to receive shaft 62 and is provided with a set screw 78 for the purpose of positioning said fan 70 in the proper vertical relation to shaft 62 and nozzles 60. Spot-welded to the underside of metal disk 72 is a series of fan blades 80. It is understood that the invention is not to be restricted to the particular fan head described, as any suitable form may be used.

The parts above described in detail are shown in assembled and running position in Figure 1. The entire mechanism is bolted to a lower metal hearth plate 82 by means of bolts 84 passing through apertures provided therefor in the lugs 17. Packing 84 is provided between the upper cylindrical surface of casing 4 and hearth plate 82 as a means of insulating against excessive heat and preventing air leaks.

The hearth assembly in which the distributing mechanism is placed is very similar to that described in my co-pending application Serial No. 729,928, filed June 9, 1934. It consists of the lower hearth plate 82, the layer of insulation 83 on top thereof, said plate 82 and insulation 83 being bolted to an internal flange 85 provided therefor on the heater base B by means of bolts 86; and an upper metal hearth plate or hearth proper 88, which is spaced from the lower hearth 82 by means of spacers 90. Said spacers are of channel section and have apertures 92 in their vertical surface for the purpose of ventilation. Said spacers are spot-welded to upper hearth 75

plate 88 and are secured to lower hearth plate 82 and insulation 84 by means of bolts 91.

A further spacer 94 of cylindrical form is placed between the hearths 82 and 88 at their center portions, said upper and lower hearths 88 and 82 respectively having central apertures of a size equal to the inside diameter of spacer 94. Upper hearth 88 is lipped upwardly as at 96 around its central aperture. Resting on said lip 96 is a flanged cylindrical member 98 which fits snugly inside of spacer 94. In assembly, said member 98 is inserted after spacer 94 has been inserted between the upper and lower hearths. The lower portion of said member 98 is then peened or bent over and around the underside of the aperture through lower hearth 82. In this manner member 98 is retained in place and at the same time retains spacer 94 and insures the relative spacing of the upper and lower hearths. The peripheral flange of member 98 extends to a diameter very nearly equal to the outer diameter of fan blades 88. This prevents recirculation of the air through the fan.

Upper hearth 88 has at its outer periphery an upstanding flange 89 for the purpose of collecting any moisture or unburned fuel which may drop from the combustion chamber wall so that it may be evaporated, or burned, as the case may be, when the temperature becomes high enough. In close proximity to the outer periphery of the combustion chamber is a series of three continuous rings, each formed in one piece or strip of sheet metal, and comprising: an air deflecting ring 100, nearest the burner head, and of the least height; an oil impingement and vaporizing ring 102, of greater height; and an outer ring 104, of the greatest height. The one piece rings 100 and 102 fit snugly upon the hearth plate 88 to form a sheltered gutter or ignition groove 101. As before stated, said rings are continuous and are positioned with respect to each other and upper hearth plate 88 by means of L shaped pieces 106 which are spot-welded to said rings and hearth plate. Outer ring 104 also fits snugly on the hearth plate 88 and may be termed a "splash ring" as it is for the purpose of confining any fuel oil which may splash from impact ring 102 within the combustion zone. An igniter 110 is provided adjacent and inwardly of ring 100 and is generally of the type disclosed in my previous application Serial No. 731,562, filed June 20, 1934.

The front portion of the heater base B is rectangularly bulged to provide for the insertion of the burner's component accessories. The forward side of said bulge is open, having a screen or perforated sheet cover 108. Said accessories consist essentially of oil metering and level valve assembly F, oil sump and air trap G, and a transformer and condenser (not shown). A bracket 112 is suitably provided to position oil metering and level valve assembly F and is so positioned that the oil level of said valve assembly—as indicated at 114 in Figure 1—is at the correct height to insure the lower portion of threads 52 of rotat-

ing portion 2 being below said oil level line. There is no novelty claimed for the oil metering and level valve structure per se, as it is of conventional type, having an oil inlet 115 and outlet 116, and as any known device having the proper characteristics will suffice, a fully detailed showing is unnecessary. However sufficient disclosure will be made to clarify the operation. With particular reference to Figure 1, oil passes from the inlet 115 through the usual oil strainer portion 117 into a chamber or reservoir contain-

ing a float 118. By means of a lever 119 the float is connected to a valve 120 which is designed to move vertically to control the upper end of a passage 121 through which oil normally is discharged to the metering portion 122 of the assembly.

The upper end of passage 121 is located below the horizontal plane of line 114, previously mentioned, and adjacent thereto and slightly above said plane a lip 123 is provided. The float and lever are designed to close the valve when the oil level tends to exceed that of the plane 114 but if for any reason the float chamber fills to a level materially above said plane, the excessive oil will be discharged over said lip 123 into a trip bucket 124.

The trip bucket 124 is suspended freely by a link 125 to one end of a lever 126 which is pivoted to the casing at 127 between its ends and which, at its other end, abuts a coil spring 128. The coil spring cooperates with the lever to yieldingly resist downward movement of the trip bucket. It will prevent the bucket from dropping until a predetermined quantity of oil has been discharged into the bucket to overcome the spring resistance. In its descent the bucket pulls the lever 126 into contact with the upper end of valve 120 to force the latter into a sealing seat in the upper end of the passage 121 and thus positively cut off the oil supply through the metering valve to the burner.

The oil metering valve per se (not shown) is of any conventional type for permitting a predetermined maximum flow of oil from passage 121 into the outlet 116 for transmission to the oil reservoir 37 of the motor assembly. It is associated with a shaft 130 having a wing nut 131 attached thereto. The quantity of flow of oil is governed by rotating said wing nut to a position which gives the desired rate of fuel flow.

A drain pipe 132 is connected at one end with a drain hole 133 provided in the upper hearth plate 88 (see Figures 2 and 3). This drain hole may be located entirely between the rings 100 and 101, or entirely inwardly of the ring 100; but preferably as illustrated in Figure 3 it is bisected by the ring 100 so that it will drain oil from both the gutter 101 and the hearth portion inwardly of said gutter. Immediately surrounding said drain hole, the hearth plate 88 has a circular raised portion 134. Drain hole 133 is formed by a downwardly turned circular lip 135 in the center of said raised portion. The lower edge of the ring 100 is notched where it passes over this raised portion. In practice the distance of the top of raised portion 134 above the top of hearth plate 88 is approximately $\frac{1}{8}$ ", for the following reason. It is evident that when the burner starts up cold, all of the fuel flung outwardly from flinger tubes 58 will not be immediately consumed. If the surface surrounding drain hole 133 were not raised, such fuel would immediately drain through pipe 132 and cause the liquid in sump G to overflow into trip bucket 124, thus causing premature shut down. By having portion 134 raised a short distance the burner is given a chance to get started, for a certain amount of fuel will have to accumulate before overflow can occur.

The connection between the receiving end of pipe 132 and the port 133 comprises a cylindrical sleeve 136 inserted upwardly through holes provided therefor in lower hearth plate 82 and insulation 83. The upper portion of said sleeve is press-fitted around depending lip portion 135 and is thus retained in place. Sleeve 136 is pipe-threaded on the outside of its lower portion and is threaded into one end of an elbow 137. Said

elbow is connected at its other end with drain pipe 132. The parts are so arranged that drain pipe 132 slopes downwardly from its connection with elbow 131 to its connection with sump G.

5 The sump or air lock G is suitably placed adjacent the trip bucket 124, and is provided with a suitable means (not shown) for retaining it so emplaced. Said sump G is substantially cylindrical in shape, having a top and a bottom, and an 10 internal baffle 138 diametrically placed and extending from the top to a point more than half way down its height. On one side of said baffle and adjacent the top of the sump is a boss having a threaded aperture which receives the 15 threaded outlet end of drain pipe 132. On the other side of baffle 138 and diametrically opposite the outlet end of pipe 132 is a spout or lip 139 which terminates above the trip bucket 124. When installed in place the sump G is filled with 20 oil or other liquid. It is evident then, that no air can leak past baffle 138 into the combustion chamber in a direction reverse to the path of overflow oil,—or, in other words, an effective air lock is formed. Any oil discharged over the lip 139 will 25 accumulate in the bucket 124 and eventually trip the latter and thus close the float valve.

There are therefore two safety means of stopping the burner operation should failure of any of the parts occur. The first is in the oil metering and level valve assembly F which prevents the 30 level of the oil exceeding a certain predetermined height, and the second is the overflow system which prevents an excessive amount of unburned oil accumulating in the hearth.

35 It may be desirable to impart a slight downward slope to the upper hearth plate in the direction of the drain hole 133 so as to prevent any excessive accumulation of oil on the hearth prior to discharge of said accumulation through the 40 drain pipe. A suitable method of providing the desired slope is to so cast the base B that the lower face of its hearth-supporting flange 85 will be gradually inclined downwardly toward the hole 133 from the side diametrically opposite 45 said hole. The hearth plate 88, which is parallel to said lower face, thus will be given a corresponding inclination which, in practice, will be about $\frac{1}{8}$ to $\frac{1}{4}$ inch.

50 In the corner of the bulge portion of the base casting opposite to that containing valve assembly F, is the transformer H. Said transformer is bolted to said base casting by means of suitable bolts 141. Said bolts 141 also perform the function of a ground connection.

55 Referring now to the electrical circuit, a suitable source of electricity is provided and a conventional switch is provided between the source and all other electrical devices, said switch being thermostatically controlled by a suitable 60 thermostat T placed in the water chamber of the heater. (See Fig. 1.) When the water in the heater has reached a certain predetermined temperature the thermostat functions to open the electric switch and thus stop the operation of the 65 entire mechanism. This is termed a temperature control and is the only one used in this invention.

70 In operation the mechanism is exceedingly simple. Assuming a cold start, the thermostat controlled switch will be closed, and when the usual main control switch (not shown) is snapped on, current flows into the transformer and the motor of the burner assembly A. A spark immediately begins to jump from electrode 150 to ring 102, and also, the rotary portion 2 of the burner 75 A starts rotating. The oil line from the reserve

tank E to the burner A is always open unless closed by trip bucket 124. The valve assembly F maintains the oil at the level of line 114 so that the lower portion of threads 52 of rotating portion 2 are always immersed for about $\frac{1}{4}$ " of their 5 length. As soon as the portion 2 starts revolving, the threads 52 will carry the oil upwardly and when it reaches the upper portion of said threads, due to centrifugal force, will divide equally, half going into each finger tube 58 and thence being 10 flung outwardly from each nozzle 60. Said oil flies toward the impact ring 102 and upon impact therewith is shattered into smaller particles. Air is supplied through apertures 10 of burner A and is carried upwardly through the center orifice 15 formed by member 98, and is then forced outwardly by fan blades 80. The air strikes the ring 100 and is deflected upwardly and outwardly, a portion of it admixing with the oil particles, thus forming a combustible mixture in the groove 20 or gutter formed by impact ring 102, hearth 88 and ring 100. Initial combustion takes place in said groove by means of the spark created across the spark gap. The groove is deep and forms an excellent area for flame propagation. As soon as 25 the rings become heated, the impinging oil is completely vaporized, and the flame rises and licks the periphery of the combustion chamber. The flame also heats the outer surface of the ring 102 to render the entire ring intensely hot 30 and capable of instantaneously vaporizing all impinging oil.

The metering device, previously described and which is controlled by wing nut 131, is necessary to provide for different operating conditions. 35 Should the ignition fail at any time, the oil return pipe 132 will provide for draining off the unburned oil and cause it to flow into the trip bucket 124, which will immediately stop the supply of oil. In like manner, should the constant level 40 part of the valve assembly F get out of order in any way, the trip bucket will operate to stop the flow of oil. The motor will continue to operate and current will continue to flow through the transformer should the trip bucket for any reason 45 be tripped. This, however, is not serious as the amount of current required is almost negligible and the fact that the burner is not doing the work it is supposed to be doing, will very soon be noticed. 50

The only wearing surfaces of the burner are the lower portion of shaft 62 and the portion 24 of sleeve 22. An extremely long bearing—as compared to the diameter—is provided between these surfaces which is conductive to low unit stresses. 55 Thrust ball 66 carries only the weight of the parts comprising rotating portion 2 and inasmuch as it is constantly bathed in oil, its wear is negligible.

Therefore, my invention comprises an extremely efficient burner having few parts and which requires a minimum of associated devices for its safe and efficient operation. Servicing of this burner is exceedingly simple. The removal of cover 108 gives access to all of the associated parts and the removal of the rotating portion 2 60 of the burner proper is accomplished merely by reaching in through the fire door and lifting it out.

It is interesting to note that the operation of 70 this burner is based in great part upon the physical law that liquids seek their own levels. Thus, the level of the fuel oil in the burner is maintained equal to the controlled level in the valve assembly F; and in the oil sump G the level of the oil on one side of the baffle 138 remains the same 75

as the oil level on the other side, so that any oil fed through pipe 132 will raise the level on the other side and cause overflow into the trip bucket.

In the preferred or suitable form of water heater D shown mounted in position upon the base B for cooperation with the burner assembly just described the heater unit is so constructed and assembled that one of its internal parts forms a combustion chamber for special close cooperation with the burner assembly, and comprises the following parts,—described without adhering to the manner or order in which they are put together.

A pair of concentric cylindrical shells, 155 and 156, are spaced by a ring 157 to which the former is welded adjacent its lower edge. The ring and the outer shell rest upon a circular gasket 158 carried by base flange 85, the latter and the ring being so shaped and of such size that when the burner assembly is added the hearth rim 89 will be disposed beyond the periphery of the shell 155 and close to the lower edge thereof, as seen in Figure 1. An integral upstanding flange 160 is formed on the base flange 85, this flange being larger in diameter than the shell 156 to permit a free fit under all conditions. The annular space between these two members is then packed with furnace cement, as at 162.

The inner shell 155 is very short in height and is capped by a dome plate 163 provided with a rim 164 which fits snugly within the upper end of the shell and is welded thereto, as shown. The shell and plate thus produce an inverted cup-shaped member which forms the combustion chamber C. A relatively small flue or pipe 165 is welded at its lower end to the center of the dome plate 163 and extends vertically upwardly for cooperation with any suitable further structure to form a water chamber 167.

As the height of the combustion chamber C is considerably less than the diameter of the hearth, and as the chamber is provided with a relatively small outlet, centrally located, an exceptionally high degree of efficiency is obtained.

This is particularly true where, as illustrated, the burner assembly is of the rotary wall flame type, with combustion taking place at the periphery and the low dome 163 serving to hold the flame down while being licked thereby to develop temperatures causing very rapid transfer of heat to the water. To further prevent the flame from elongating and tending to run into the small central outlet, an overhanging grillwork (not shown) will be mounted on the oil vaporizing ring 162.

As another example, the grillwork may be formed by utilizing a ring 162 of greater height than that here shown, with its upper edge turned inwardly to overhang the gutter and provided either with simple perforations or with spaced upright vanes struck out from the material to afford spaced slots. Likewise the ring 164 might be modified in similar fashion.

It is understood that, although the invention is disclosed in connection with a hot water heater, it is not to be so restricted, as it may be used with other heating devices. The invention consists principally in the burner mechanism and its associated parts.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. In a liquid fuel burning apparatus of the type comprising a combustion chamber closed at the bottom by a substantially horizontal hearth and embodying means for conveying liquid fuel into the chamber and projecting it in liquid form substantially horizontally over the hearth; a fuel impact wall arranged in the path of the projected liquid fuel; means cooperating with said wall to form a gutter for collection of unconsumed fuel; means for removing any excess of unburned fuel from the chamber, said means being in communication with said gutter, and also with the upper hearth surface at a point outside the gutter; and means cooperating with said removing means to stop the liquid fuel projection in response to discharge of a predetermined quantity of unburned fuel from said hearth and said gutter into said removing means.

2. In a liquid fuel burning apparatus of the type comprising a combustion chamber closed at the bottom by a substantially flat sloping hearth and embodying means for projecting liquid fuel into the chamber, said hearth being provided with an overflow port adjacent the lower side thereof with its overflow edge raised slightly above the hearth surface surrounding the port, said hearth having sufficient slope from one side to the other in the direction of said overflow port to ensure full drainage into said port the hearth being otherwise closed around the fuel projecting means to collect and hold some unburned liquid fuel, means for receiving unburned liquid fuel discharged through said port, and means cooperating with said receiving means to interrupt the projection of liquid fuel into said combustion chamber when a predetermined quantity of liquid fuel has passed over said overflow edge of the port for drainage into said receiving means.

3. In a liquid fuel burning apparatus of the type comprising a combustion chamber closed at the bottom by a substantially horizontal hearth and embodying centrally disposed means for projecting liquid fuel into the chamber, said hearth being provided with an overflow port adjacent the periphery thereof, said hearth having sufficient slope from one side to the other in the direction of said port to ensure fuel drainage into the port without accumulation of excessive unburned fuel in the chamber, and means for receiving the liquid fuel discharged from said port and for interrupting the fuel projection upon receipt of a predetermined quantity of the discharged fuel.

MILTON A. POWERS.
